DESIGN FOR A CAPE.

Design No. 6,635, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. 6,635, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The accompanying photographic illustration clearly represents my design for a circular garment, the main peculiarity of which is the fringe or border *a* of the hood *A* and body of the garment, this being of a character so clearly shown as to require no minute description. The hood is of a triangular shape, is opened down the center, and ornamented by a cord, *b*, and pendent tassels *c* and *d*.

Irrespective of the colors employed, I claim—
The design for a circular garment, substantially as described, and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
